UNITED STATES PATENT OFFICE.

GEORGE F. DOWNS, OF BUFFALO, NEW YORK.

WATER-COOLED DOOR FOR FURNACES.

1,312,168.

Specification of Letters Patent. Patented Aug. 5, 1919.

Application filed November 14, 1918. Serial No. 262,478.

To all whom it may concern:
Be it known that I, GEORGE F. DOWNS, a citizen of the United States, and a resident of Buffalo, in the county of Erie and State 5 of New York, have invented certain new and useful Improvements in Water-Cooled Doors for Furnaces; and I do hereby declare that the following is a full, clear, and exact description thereof, reference being 10 had to the accompanying drawings, and to the letters of reference marked thereon, which form a part of this specification.

This invention relates to improvements in water cooled doors for furnaces and consists of the matters hereinafter described and more particularly pointed out in the appended claims.

The invention as illustrated herein, is shown embodied in a door for open hearth 20 furnaces, where its use is of especial advantage owing to the intense heat; but, as will appear, it is in no way limited to such use as it may be advantageously employed in connection with other types of furnaces.

25 The several objects and the novel features of the invention will be pointed out as I proceed with my specification.

In the drawings:

Figure 1 is a view representing in elevation a part of the side wall of an open hearth furnace, with my improved water cooled door in place thereon.

Fig. 2 represents a vertical section through said side wall and through said door, the 35 plane of the section being indicated by the line 2—2 of Fig. 1.

Fig. 3 is a view showing, on an enlarged scale, the door itself in front elevation, with the front wall partially broken away.

40 Fig. 4 is a view representing a rear elevation of the door.

Fig. 5 shows a top plan view of the door on a still larger scale.

Fig. 6 presents, on the scale of Fig. 5, 45 a transverse section through the door in a plane indicated by the line 6—6 of Fig. 3.

Fig. 7 shows, on the scale of Fig. 5, a vertical section through the door in a plane indicated by the line 7—7 of Fig. 3.

50 Referring now to that embodiment of my invention shown in the drawings and particularly as when applied to an open hearth furnace:—

10 indicates a part of the side wall of an 55 open hearth furnace adjacent one of the fur-

nace door openings; 11, the door opening; and 12 indicates the improved door. The door 12 is hung and arranged in a familiar way to be raised or lowered to uncloset or close the opening 11, resting normally on a 60 base or sill 13 when in closed position, and being adapted to be raised or lifted by means of links 14, 14, pivotally connected to ears 15, 15 at the top of the door, and being operable by a hydraulic or other device 16, in a well 65 known manner.

The door comprises an outer cast metal, hollow shell 17; a removable conduit 18 located on the inner face of said shell and following the outline of the door; and a refractory lining 19 which is preferably supported and held in place by means of the conduit 18. The shell 17 has a flange 20 at the top and has side flanges 21, 21. A vertical rib or web 17^b connecting the front 75 and rear walls of the said shell and extending along the median line of the door from the top to a point somewhat above the bottom, divides the water compartment 17^a in the shell into two parts connected by a passage at the bottom.

The conduit 18 consists of a pipe having upright branches 22, 22 which are located adjacent to the side flanges 21, 21 of the door shell 17, and a horizontal branch 23. 85 The side branches 22, 22 extend through suitable holes or openings formed in the top flange 20. The upper end parts of said branches are threaded to receive lock nuts 22^a, 22^b, by means of which the conduit as a 90 whole is supported in place. One of the branch pipes 22 is connected by a reducing couple 27 to a pipe 24 which is telescoped upon an upright pipe 37 of smaller diameter. The pipe 37 is connected to a 95 main water supply pipe 39,—a hose 38 being interposed in the connection to provide for greater flexibility when the door is raised or lowered. The other branch 22 of the conduit is connected by a coupling 27 to a 100 short upright pipe 25, which is closed at the top except for a small vent 25^a and to which is connected a discharge pipe 26 that is adapted to direct a flow into the upper open end of the hollow shell 17. Upon the detachment of the couplings 27 and the removal of the lock nuts 22^a, the conduit may be withdrawn downwardly and removed from the door, to be replaced by another one 105 of the same kind. An overflow pipe 28 is 110

110

attached to the pipe 24 of the supply system, and is so arranged as to direct any overflow into the top of the hollow shell 17.

The conduit 23 is preferably made in a somewhat elliptical cross section, as clearly shown in Figs. 6 and 7, with the inner face flat and inclined inwardly and toward the center of the door. By this construction, the conduit itself provides a means for retaining the lining of fire brick 19 in place. The top flange 20 has its inner face 20^a likewise inclined inwardly and toward the center of the door for the same purpose. After the lining is in place, it may be securely locked by means of the lock nuts 22^a which act to draw up the conduit.

Near the top of the door there is formed in the cast metal shell 17, a hole or opening 29 to which is connected a discharge pipe 30. Said discharge hole is made in that compartment which is farther from the discharge pipe 26, so as to insure a circulation of the cooling water. The discharge pipe 30, as shown, is connected by a branch pipe 25³¹ to a depending pipe 32, which telescopes within an upright receiving pipe 33 of larger diameter, in such manner that as the door is raised and lowered, connection will always be maintained between the pipe 32 and the pipe 33. The pipe 33 leads to a suitable source of final discharge of the water.

The improved door is provided with the usual peep hole 34, which extends through the cast metal part or piece of the door and 35 also through the fire brick lining. Said peep hole is closed by means of a plate or disk 35 which is guided, supported and held in place by means of top and bottom flanges 36 in the usual way.

40 It will be apparent that water supplied to the pipe 24 will pass, first through the entire length of the conduit 18, thus providing a cooling medium for the lateral margins and the bottom margin of the door. It will thence be discharged through the discharge pipe 26 into the cooling water compartment 17^a in the shell piece 17, after circulating through which, it will be discharged into the pipe 30. Thus, as described and preferred, the circulatory systems of the conduit and of the front piece of the door are interconnected but it will be manifest that this is not essential and that they may be independent.

55 The overflow pipe 28 takes care of fluctuations in pressure in the supply main, which are apt to occur from time to time on account of the variations in the demands made on said main. A sudden increase of flow 60 would cause a splash at the telescoping connection between the pipe 24 and the pipe 37; but this is prevented by the said overflow pipe.

At the sides of the shell piece 17 at the 65 bottom, are provided threaded openings

which are closed by plugs 40, 40. These openings are for the purpose of cleaning out the compartment which may be washed out by flowing water that is permitted to escape through said openings.

The many advantages of the improved water cooled door will be apparent to those familiar with the art. The outer door piece or shell may be made of such thickness and strength as to successfully resist any and all 70 shocks to which it may be subjected, and as it is water cooled, and in addition is not directly exposed to the flame, its life is almost indefinite. The inside marginal edges at the sides and at the bottom of the door, 75 which are exposed to the flame, are provided by the water cooled conduit and if, for any cause, said conduit begins to leak, the door may be removed and a new conduit substituted for the defective one, and this without 80 impairing the value or strength of the outer cast metal door piece. Again when the refractory lining wears away or in any way becomes defective, it may be replaced at the cost of little effort and labor.

90 While I have described my improved door as being particularly applicable for use with open hearth furnaces and have referred to certain details of mechanical construction and arrangement as appertaining more particularly to such use, it will be understood that the invention is in no way limited thereby except as may be pointed out in the appended claims.

I claim as my invention:

1. A door for furnaces comprising a water cooled, front metal piece, provided with a top and with side flanges on its inner face, and a second water cooled piece consisting of a conduit having two side branches and a bottom branch, the side branches being engaged against the side flanges of the front piece and extending through openings provided in the top flange of said front piece, and means for detachably supporting said second piece upon the top flange of said front pieces.

2. A door for furnaces comprising a water cooled, front metal piece, provided with a top and with side flanges on its inner face, a second water cooled piece consisting of a conduit having two side branches and a bottom branch, the side branches being engaged against the side flanges of the front piece and extending through openings provided in the top flange of said front piece, lock nuts threaded upon the said side branches of said conduit above the top flange of said front piece, and a refractory lining located against the inner face of the front piece and held and locked in place by means of said conduit.

3. A door for furnaces comprising a hollow, cast metal front piece, said front piece being provided with flanges on its inner face

- at the top and sides thereof, a metal conduit placed against the inner face of said front piece having a horizontal branch at the bottom of said front piece and side branches engaged within the side flanges of said front piece, said side branches projecting through openings in the top flange of said front piece, lock nuts threaded upon the upwardly projecting ends of said side branches of the conduit, and a refractory lining placed against the inner face of said front piece, and said conduit being of a cross section adapted to engage and retain said refractory lining in place.
- 5 5. A door for furnaces comprising a rectangular cast metal, water-jacketed front piece, having a rearwardly extending flange along its top inner edge, a conduit having side and bottom members, arranged on the inner rear face of and outlining the sides 40 and bottom of said front piece, the side members of said conduit extending through and being removably attached to said rearwardly extending flange of said front piece, and means providing a water connection between one of the side members of said conduit with the water jacket of said front piece.
- 10 6. A door for furnaces comprising a hollow, cast metal front piece, said front piece being provided with flanges on its inner face at the top and sides thereof, a metal conduit placed against the inner face of said front piece having a horizontal branch at the bottom of said front piece and side branches engaged within the side flanges of said front piece, said side branches projecting through openings in the top flange of
- 15 7. said front piece, lock nuts threaded upon the upwardly projecting ends of said side branches of the conduit, a refractory lining placed against the inner face of said front
- 20 piece, said conduit being of a cross section adapted to engage and retain said refractory lining in place.
- 25

In testimony that I claim the foregoing as my invention, I affix my signature in the presence of two witnesses, this 11 day of November, A. D., 1918.

GEORGE F. DOWNS.
